UNITED STATES PATENT OFFICE.

EARL THOMAS FLOYD, OF NEAR TEMPLE, PENNSYLVANIA, ASSIGNOR TO THE NOLDE AND HORST COMPANY, OF READING, PENNSYLVANIA, A CORPORATION OF PENNSYLVANIA.

STRIPING ATTACHMENT FOR CIRCULAR-KNITTING MACHINES.

Application filed April 29, 1926. Serial No. 105,596.

My invention relates to improvements in vertical striping mechanism for circular knitting machines of the type more fully shown and described in the U. S. Letters Patents to Frank W. Robinson Nos. 1,077,304, of November 4, 1913, 1,203,181, of Oct. 31, 1916, and 1,357,254, of Nov. 2, 1920. And more particularly it consists in a selective plurality of means for determinedly imparting and controlling needle-engaging swings to the several striping thread fingers employed, whereby a maximum variety of stripes both continuous and interrupted and of various widths and conformation, may be readily and automatically produced. My invention is fully described in connection with the following drawing, reference to which will be more fully made, and the novel features are set forth in the appended claims.

Fig. 1 is an elevation, partly in longitudinal section, showing an embodiment of my improvements as applied to a known form of circular knitting machines.

Figs. 2 to 5 are perspective views showing variant forms of means within the spirit of my invention, for imparting needle swings to the thread guide finger.

Referring to Fig. 1, the needle cylinder 2, needles 3, cam cylinder 4 and frame or bed plate 5, are parts of a known circular knitting machine in which the cam cylinder 4 is rotated, while the needle cylinder 2 is held against rotation. A fixed bracket 8, mounted on the frame 5, supports a finger-carrying head 10 in axially adjusted suspension above the needles 3, by means of stem portion 11 engaged in the apertured end 9 of said bracket; fixed collar 12 positioning said head in lowered operative position and set screw 13 retaining said head when raised out of operative position.

Mounted around the periphery of the head 10, are a circular series of striping thread fingers 21, each having a universal-joint suspension in a bearing block 22 fixed to said head 10 and each of said fingers 21 carrying an independent striping or embroidery thread 15, in its depending needle-engaging end 20, which threads are wrapped about determined needles and interknit with the regular loops on the latter when successive needle-engaging swings are imparted to each finger end in the manner set forth in said

prior Robinson patents heretofore mentioned

Such known needle-engaging swinging movement of each finger end 20 has heretofore been imparted by a cam 30, rotatably carried by cam cylinder 4, acting upon a pair of rollers 27, 28 carried at the free end 60 of a carrier member 25 rigidly projecting laterally from the universal suspension point of each finger 21; said cam acting, in passing said rollers and in conjunction with some form of retracting spring as 31, to swing 65 said finger end 20 through the circle of needles 3, along the outside of the latter to include a determined number of needles to be wrapped, back through the circle of 70 needles, and return within the circle of 75 needles to the starting point. This swinging movement, as controlled by some form of means for determinedly varying the same in successive rotations of the cam 4, as devices 35, 35 similar to that shown and described in Patent 1,203,181 before referred to, has long been employed in producing plaited or embroidery stripes on the knitted fabric.

Inherent defects in the construction thus briefly described and long employed, have limited the number of striping fingers 21 that may be employed in the necessarily restricted circumference of the circle of needles 3, and also limited the individual control of 85 the several fingers, requiring inventive ingenuity and radical rebuilding of the striping attachment to produce stripes of various designs, which for purposes of economy should be produced on a single machine by 90 mere readjustment of readily set cam-engaging members and pattern-chain lugs.

With such universal possibilities of a striping attachment in mind, my improvements comprise the use of a plurality of actuating 95 cams 30, 30', 30'', each arranged to act in a different horizontal plane, and each cam movable into and out of finger-operating position as controlled from a pattern chain or drum 62; the lugs of the latter, in the 100 simple arrangement indicated in Fig. 1, acting on levers 56, 56', 56'', which in turn project retracted rods 54, 54', 54'', and the latter acting through respective star-wheel cams 65, 65', 65'' to swing levers 53, 53', 53'' 105 connected respectively to the cams 30, 30',

30" carried in bracket 66 secured to rotated cam cylinder 4.

With such plurality of cams 30, 30', 30" acting in different planes, my improvements 6 consist further in providing each finger 21 with means by which it may be acted upon by any one or all said cams in successive rotation to impart a determined needle-engaging swing to its depending end 20. Such 10 means may be effected in various ways: For instance, to the right in Fig. 1, and in Fig. 2 I have indicated the rollers 27 and 28, with their supporting plate 271, as provided with a stem 25^a which may be secured to carrier member 25 projecting laterally from the universal suspension point of finger 21, or to similar members 25' or 25" projecting laterally from the finger 21 respectively above and below member 25. Three sets of 15 such rollers 27-28 may be employed at one time, or two sets, or a single set, as required, but each set when secured to its respective member 25 or 25' or 25", will be carried in a cam plane and be actuated by its 20 respective cam when the latter is projected to operative position by pattern chain 62 as heretofore described. Thus finger 21, when three sets of rollers 27-28 are employed, may be actuated in successive rotations of the 25 cylinder 4 by any one of cams 30, 30', 30" so as to impart a needle-engaging swing to its depending end 20. And by arranging adjacent fingers 21 with but a single set of rollers 27-28 each in a different plane to 30 be acted upon by one of the three simultaneously projected cams 30, 30', or 30", a very close arrangement of the fingers is possible 35 permitting additional vertical stripes not possible heretofore.

40 Fig. 3, and to the left of Fig. 1, shows a modified manner of carrying the rolls 27-28, a plate 272 being secured to member 25 and being of sufficient height to provide for mounting said rollers 27-28 in any or 45 all the cam planes.

Fig. 4 shows the members 25' and 25" connected by a strip 273, and the rollers 27-28 mounted on plates 274 readily secured to or removed from the strip 273 as desired.

50 Fig. 5 shows strip 273 of Fig. 4 secured to member 25 only, and indicates three rollers to impart a greater swing, to right and left of a center rest, similar to the showing of Patent 1,203,131 heretofore mentioned. This 55 Fig. 5 also indicates that instead of the single needle engaging end 20 of finger 21, the end of the latter may be made removable and a double or triple prong finger 20' substituted.

60 The finger-swing limiting devices 35, 35, indicated, are similar to that shown in Patent 1,203,131, aforesaid, and each device 35 will control certain fingers 21, and each may be separately shifted to vary the needle 65 swings of its respective fingers as heretofore,

by its respective rod 36 or 36^a, the latter being controlled from pattern chain 62 through its respective rod 50, or 50^a acting on its connected cross arm 37 or 37^a. Both devices 35, 35 may be suspended below the finger-carrying head 10 as shown, or one or an additional third device 35 (not shown) may be employed above the latter somewhat in the manner disclosed in Patent 1,357,254, heretofore mentioned. 75

By proper employment of sets of rollers 27-28 and manipulation of cams 30, 30', and 30", together with adjusted lugs on chain 62 to cooperatively control devices 35, 35, a great variety of patterns may be produced on the one machine by mere readjustment of readily interchangeable parts, and by using different pronged finger ends 20' and other modifications suggested in the several Robinson patents referred to, and other known means of similar nature, an infinite flexibility of the machine is provided for, as well as increase in the number of stripes producible as heretofore set forth. While the drawings show a rotated cam cylinder 4 and fixed needle cylinder 2, it is obvious that with slight changes known in the art, the cylinder 4 may be fixed and the knitting cylinder rotated, in such latter case the fingers 21 being rotated with the latter, and the cams 30, 30', 30" held stationary. Other modifications within the spirit of the invention may readily be made. 95

What I claim is:

1. A vertical striping mechanism for circular knitting machines comprising a striping thread finger having a universal-joint suspension point, and a plurality of finger-operating cams arranged in parallel horizontal planes; said finger having rigid laterally extending carrier means and spaced-apart cam-engaging projections attachable to said carrier means in one or another of the cam planes. 100

2. A vertical striping mechanism for circular knitting machines comprising a striping thread finger having a universal-joint suspension point, and a plurality of finger-operating cams arranged in parallel horizontal planes; said finger having rigid laterally extending carrier means and spaced-apart cam-engaging projections attached to said carrier means in different planes corresponding with the different cam planes. 110

3. A vertical striping mechanism for circular knitting machines comprising a plurality of striping thread fingers having individual universal-joint suspension points lying in a common horizontal plane, and a plurality of finger-operating cams arranged in parallel horizontal planes, each of said fingers having a rigid member extending laterally therefrom and carrying a plurality of spaced-apart cam-engaging projections, the projections of the several fingers being 125

130

variously arranged in relation to the cam planes.

4. A vertical striping mechanism for circular knitting machines comprising a circular series of striping thread fingers having individual universal-joint suspension points lying in a common horizontal plane, and a plurality of finger-operating cams arranged in parallel horizontal planes and each selectively movable into and out of operative position, each of said fingers having a rigid member extended laterally therefrom, and spaced-apart cam-engaging projections attachable thereto in one or another of the cam planes.
5. A vertical striping mechanism for circular knitting machines comprising a circular series of striping thread fingers having individual universal-joint suspension points lying in a common horizontal plane, and a plurality of finger-operating cams arranged in parallel horizontal planes and each selectively movable into and out of operative position; each of said fingers having a rigid member extended laterally therefrom and carrying a plurality of spaced-apart cam-engaging projections, the projections of the several fingers being determinedly arranged in one or another of the cam planes.
6. A vertical striping mechanism for circular knitting machines comprising a plurality of striping thread fingers having individual universal-joint suspension points lying in a common plane, and a plurality of movable finger-operating cams arranged in

parallel horizontal planes, means for selectively moving said cams into and out of operative positions, variable stops to limit the needle-engaging swing of individual fingers and means to determinedly vary the same, and each of said fingers having a rigid carrier member extended laterally therefrom, and spaced-apart cam-engaging projections attachable to said member in one or another of the cam planes.

7. In combination with a knitting machine having a circular series of knitting needles, of a striping mechanism comprising a finger-carrying head axially suspended above said needles, a circular series of striping thread fingers having individual universal-joint suspension bearings on said head, and each finger having a rigid member extended laterally therefrom whereby needle engaging swings may be imparted to the free ends of said fingers, vertically movable stops to variably control such needle-engaging swings of individual fingers and automatic means for determinedly controlling the same, a plurality of finger-operating cams arranged in different horizontal planes, automatic means for determinedly moving said cams into and out of operative position, and spaced-apart cam-engaging projections attached to said laterally projected finger members in different planes corresponding with the different cam planes.

In testimony whereof I affix my signature.

EARL T. FLOYD.
